P. Don,

Splitting Leather,

Patented July 12, 18

Fig. 1

Fig. 2.

July 12, 1810

The Schedule is fixed to and annexed to the said Letters Patent and making part of the same containing a description
of the merits of the said Plumbeous Pew himself of his cylindrical Leather Splitting Mill.

The invention of this improvement called the "Cylindrical Leather Splitting Mill" consists in
constructing the machine with a cylinder on which the knife is fixed to split the Leather. This
cylinder is made of wood with an iron or wooden axis on which it turns. The end of the cy-
linder may be made of iron, or lead, iron about two feet or more in diameter. The knife is fixed
in the circumference of this cylinder parallel with ^{and is made} said axis, or more sideways, by a cramp to
which communicates with the hole round which the leather is drawn when it is split.
This cylinder is fixed in a proper frame. When in operation the knife is turned so as the
said cylinder do as to be under the centre of it. Directly under the knife a roller is firmly
nearly fixed on the frame which serves as the gauge of the leather while splitting and is
made to fit the edge of the knife so as to allow half the thickness of the leather to pass be-
tween it and the edge of the knife. The roller is regulated to this roller according as the leather
is may require by wedges on the top of the boxes of the pins of said cylinder axes.

Above the edge of said knife another roller is fixed in said cylinder with springs in
its pins in the ends of said cylinder so as to press said roller down closer to the knife. The
said knife and keep the leather also pressed upon said roller under the edge of said
The cylinder has only a quarter section of its circumference in the other part is left open.
To this quarter section the knife is fixed and the machinery for giving motion to the knife.
This motion to the knife is produced by a roller put into said cylinder with an oblique or
spiral groove. A lever fixed in the cylinder so as to move said knife end ways is operated
upon by said spiral groove, and is vibrated one way and the other by a crank on said
roller to which crank an arm is fixed which communicates with the primary motion
of the machine. Back of the knife is constructed a spreader which is made of wood
together like jaws having notches cut in them obliquely each way so as to spread the leather
as it is drawn in while splitting. The under jaw is on the frame. The upper is on the cylinder.
When the leather is to be put in the said cylinder is turned each way to bring the knife up-
wards, or at the top of the cylinder which lies horizontally in which position it is easily taken
out and sharpened and put in again. Two sloping plates are fixed to the end of the cylinder
so as to allow the edge of the knife to come to its proper place and bind to be kept firmly.

1336

skin splitting the leather. A round square roller with three whisks filled w. d. is fitted into the former round wheel the leather is drawn while splitting. The said whisks are removable on said square roller so as to prevent the leather from stretching. A pair of nippers with wire jaws is placed with proper leather straths to this roller. These nippers take hold of the leather & in going said conical roller they haul it through and as it is split it then is wound on this roller. On one end of this conical roller a conical and non-wheel line fast in diameter is firmly fixed. This conical wheel is turned by a pinion to which a cord & is, by which the whole machine is made to operate. Another roller is also fixed on the frame so as to keep the leather while splitting up close to the surface of the cylinder. The roller under the edge of the knip and which forms the gauge is made of cast iron about five inch. in diameter and is accurately turned. The other rollers are made of hard wood. The sides of Newts leather as well as sheep and other skin, may be split by this machine while wet so as to make two skins out of one.
